UNITED STATES PATENT OFFICE

125,174

DESIGN FOR A PIANO-PEDAL-STOOL

Charles Harvey Churchill, Cortland, N. Y.

Application September 18, 1940, Serial No. 95,181

Term of patent 7 years

To all whom it may concern:

Be it known that I, Charles Harvey Churchill, a citizen of the United States, residing at Cortland, in the county of Cortland and State of New York, have invented a new, original, and ornamental Design for a Piano-Pedal-Stool, of which the following is a specification, reference being had to the accompanying drawing, forming part thereof.

Figure 1 is a perspective view of the piano-pedal-stool, showing one side and end. Figure 2 is a perspective view showing the other side and end.

I claim:

The ornamental design for a piano-pedal-stool, as shown.

CHARLES HARVEY CHURCHILL.
